UNITED STATES PATENT OFFICE.

JOHN W. SMITH, OF MINNEAPOLIS, MINNESOTA, ASSIGNOR TO UNITED STORES SUPPLY COMPANY, OF MINNEAPOLIS, MINNESOTA, A CORPORATION.

CLEANING POWDER.

1,416,240.

Specification of Letters Patent. Patented May 16, 1922.

No Drawing.

Application filed January 31, 1921. Serial No. 441,512.

To all whom it may concern:

Be it known that I, JOHN W. SMITH, a citizen of the United States, resident of Minneapolis, in the county of Hennepin and State of Minnesota, have invented certain new and useful Improvements in Cleaning Powders, of which the following is a specification.

This invention relates to improvements in cleaning powders containing acid sodium sulphate or, as it is also known, sodium bisulphate. This chemical makes an excellent cleaning agent and is one that can be obtained in large quantities at relatively low price in the form of nitre cake, a present commercial byproduct which includes acid sodium sulphate. The source of nitre cake as a by-product is too well known to merit further comment. A great disadvantage in the use of acid sodium sulphate, either in its chemically pure state or in the form of nitre cake, as a cleaning powder resides in the fact that it is deliquescent. This attribute causes this material to conglomerate upon exposure to atmosphere or other moisture and finally to assume the condition of a hard cake. Such attribute greatly detracts from its value as a cleansing agent. This is particularly disadvantageous under those conditions where it is highly desirable to employ a cleansing medium in granular or powdered form so that the medium may be freely sprinkled from a container of the common form and sizes in general commercial use. Expensive hermetically sealed containers are efficient until the container is opened whereupon the unused portion of the material rapidly hardens and cakes and its flowing properties cease and its value for the majority of its uses is minimized.

Various combinations have been tried to retain the acid sodium sulphate in its granular or powdered form. Sodium chloride has been added, powdered silicate of magnesium has been added or substituted as have various other materials. The sodium chloride is deliquescent and aggravates the hardening and caking attribute while the other materials are expensive and the merchantable product is relatively costly.

Prolonged experimentation and severe and varied tests have resulted in the employment, in combination with the acid sodium sulphate, of powdered wood. The wood preferably used is that which is commercially known as wood flour. The wood flour is not deliquescent and, mixing readily with the acid sodium sulphate, enters the interstices between the particles thereof and substantially coats the same. Upon contact with water, in the cleansing operation, the wood flour is washed from the granules and does not interfere with the well-known effective cleansing action of the acid sodium sulphate. Furthermore, if the cleansing operation involves any rubbing action, the wood flour has the added advantage of providing a slight abrasive function.

The present preferred proportions of the two constituents of the novel composition are: Seventy per cent (70%) by volume of acid sodium sulphate, to thirty per cent (30%) by volume of wood flour.

Not only is a new and effective cleaning powder provided that retains its advantageous powder form for prolonged periods, but also this new powder may be inexpensively produced from two materials, both of which are substantially by-products.

It is to be understood that the invention is not limited to the exact proportions herein set forth as the proportions may be varied with wide limits without losing the benefits of this advantageous composition.

Having thus described my invention, what I claim as new and desire to secure by Letters-Patent is:

1. A cleaning powder including a mixture of acid sodium sulphate and powdered wood.
2. A cleaning powder including a mixture of acid sodium sulphate and powdered wood substantially in the proportions of seventy per cent by volume of acid sodium sulphate to thirty per cent by volume of powdered wood.

In witness whereof, I have hereunto set my hand this 6th day of January 1921.

JOHN W. SMITH.
